Specification for Design.

Patented Jan. 1, 1918.

Application filed October 29, 1917. Serial No. 199,195. Term of patent 7 years.

To all whom it may concern:

Be it known that I, NORMAN MACBETH, a subject of the King of Great Britain, and a resident of New York city, county of New York, State of New York, have invented a new, original, and ornamental Design for Lamp-Fixtures, of which the following is a specification.

My design is represented in the accompanying drawing. Figure 1 is an end elevation of the article embodying my design. Fig. 2 is a side elevation of the same.

I claim:

The ornamental design for a lamp fixture as shown.

In witness whereof I have hereunto set my hand at the borough of Manhattan, city and State of New York, this 24th day of October, 1917.

NORMAN MACBETH.

In presence of—

ZITA M. GRAHAM,
ISABEL R. RICHARDS.
